INVENTOR

R.E. Wise

WITNESS:

BY *Victor J. Evans*

ATTORNEY

UNITED STATES PATENT OFFICE.

BRUCE D. WOOLEY, OF JOHNSTOWN, OHIO.

WALL-PAPERING DEVICE.

Application filed December 31, 1926. Serial No. 158,273.

This invention relates to paper hanging and more particularly to a tool for hanging paper upon a ceiling or the like.

One of the objects of the invention is to provide a paper hanging tool that can be used with maximum efficiency by persons unskilled in the art of hanging paper.

A further object of the invention is to provide a paper hanger's tool that will hold and properly position wall paper and the like with respect to a ceiling or the like whereby the paper can be properly matched and hung in an expeditious manner with very little effort on the part of the user.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side elevation of my tool in use.

Figure 2 is a perspective view thereof with the handle removed therefrom.

Figure 3 is a sectional view taken on line 3-3 of Figure 2.

Figure 4 is a fragmentary view of the guide arm.

Referring to the drawings in detail the reference numeral 1 indicates the body of the tool and which as best shown in Figure 2 of the drawings is of elongated formation and preferably formed from a resilient flat strip 1 curved to provide the U-shaped configuration as shown. Secured to one end of the body 1 through the instrumentality of rivets 2 is a metallic clamp adapted to receive a strip of flexible material 3, while integrally formed with the opposite end of the body 1 is an arm 4 which is secured to the body at its central portion and is preferably of a length of the usual width of wall paper. This arm 4 is curved upon itself in substantially inverted channel shape formation so as to provide a smooth upper surface to allow the wall paper to slide thereover without injury thereto as will be apparent. However, I have provided a covering of fabric material 5 for the

arm 4 so that it will be practically impossible for the arm to injure paper during the hanging thereof.

Secured to the body 1 preferably midway its ends and extending from the bottom thereof is a handle 6 of any desired length, whereby the tool can be conveniently used by a person standing on the floor or a supporting means.

From the above description and disclosure of the drawings, it will be obvious that I have provided a tool that can be efficiently used by persons unskilled in the art of hanging paper upon ceilings and the like and the paper is supported between the arm 4 and the flexible material 3 and by forming the body 1 of resilient material, it will be obvious that the paper is stretched so that the figures thereof may be properly matched. The flexible material is adapted to apply the paper to the ceiling and by wiping the paper with the same as suggested in Figure 1, it will be obvious that the paper will properly adhere to the ceiling and the arm 4 is primarily designed for guiding the paper when applying the same.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A paper hanger's tool of the character described comprising a handle, an elongated body formed of resilient material arranged in U-shaped configuration, a clamp secured to one end of said body, flexible material secured in said clamp, an arm formed in substantially inverted channel shaped formation and fixed to the opposite end of said body.

2. A paper hanger's tool of the character described comprising a handle, a resilient strip carried by said handle, and being fixed midway its ends thereto, said strip being of substantially U-shaped formation, a wiper secured to one end of said strip, a guide arm secured to the opposite end thereof and a covering for said guide arm.

In testimony whereof I affix my signature.

BRUCE D. WOOLEY.
